UNITED STATES PATENT OFFICE.

GRACE W. JENNINGS, OF MEDFORD, MASSACHUSETTS.

SHIELD FOR WINDOWS.

1,195,681.

Specification of Letters Patent. Patented Aug. 22, 1916.

Application filed April 8, 1915. Serial No. 19,934.

To all whom it may concern:

Be it known that I, GRACE W. JENNINGS, of Medford, in the county of Middlesex and State of Massachusetts, have invented a new and useful Shield for Windows and the like, of which the following is a specification.

The main object of my invention is to provide an effective shield against wind, rain, etc., for windows or the like and in the preferred form a window shield which is self-supporting; light in weight; flexible so as to be easily disposed of when not in use; adjustable to different sizes of windows; useful as a protection against wind and rain; held in place without fastening strips and without marking the window frame and useful even when screens are in position.

My invention consists mainly in a panel provided with flaps or projections to close the joints between the panel and window frame and also to provide adjustment for windows of different sizes.

Another feature is a flexible waterproof panel.

Other features will be pointed out below.

In the drawings: Figure 1 is an elevation partly in section of a window shield embodying my invention; Fig. 2 is a perspective view illustrating the application of the shield to a window; and Figs. 3 and 4 are details of the rod and are described below.

Panel A has a portion a at its top looped over and connected to the body by fine stitching as indicated at a' . At the bottom the panel is turned back upon itself and stitched at a^2 , the end of the turned back portion being stitched to the body portion at a^3 , a passage being provided between the lines a^2 and a^3 of the stitching for the rod B. Panel A is preferably of white double-faced rubber sheeting but I may use waterproof cloth, such as cravenette, enamel cloth or single-faced rubber sheeting or other suitable flexible waterproof material.

The rod B is shown in Fig. 3 and comprises a member usually made, as indicated on a larger scale in Fig. 4, by brazing together the portions b , b' and b^2 the latter being interiorly threaded at b^3 and this threaded portion being engaged by the threaded portion b^4 of member b^5 which telescopes within the other member of the rod. One end of member b^5 enters the end

piece b^6 and bears against a spiral spring b^7 . The portion b and the piece b^6 are made with heads b^8 and b^9 provided with recesses in which the rubber grippers b^{10} and b^{11} are held. It will be observed that fairly accurate adjustment of the length of the rod by screwing member b^5 with relation to the other threaded member may be had but final adjustment is provided by spring b^7 . Rod D is just like rod B and therefore needs no independent description, rod D passing through loop a .

The bending back of the bottom of the panel forms a bottom flap a^4 and I also provide side flaps a^5 and a^6 , these flaps extending toward the outside of the window frame as indicated in Fig. 2 and closing the joints between the panel and the window frame so as to exclude wind, rain and moisture, and these flaps have a very important additional function in that they make the shield adjustable for different sizes of window frames and particularly for different widths of the frames as the side flaps will take care of widths greater than the width of the body of the panel. It may also be noted that if a frame is smaller than the normal width of the body portion, the latter may be crumpled together and thus adjusted. It will be clear that the two rods, one near the top and one near the bottom of the panel, support the panel and hold it in position, the rubber portions gripping the window frame without marking or marring the latter and without using any fastening strips. The rubber grippers are readily moved about and the rods may occupy positions nearer to each other than those shown if such closer adjustment is desired.

When the shield is in place the flaps act as valves and the more wind or rain the tighter the flaps close the joints, the inner sash being preferably lowered to the line E which prevents the entrance of rain or undesired air, the rain flowing down the side flaps and outward from the bottom flap. The reason why the flaps act as valves, as above-mentioned, is that they are sufficiently loose to bear against portions of the window frame as clearly illustrated in Fig. 2, so that, while they might yield to permit the outflow of air, the moment that there is any tendency of air to blow in through the window opening, said flaps will bear against the window frame and prevent any such inward flow of

air as would carry with it particles of precipitation. As is well known, when a window is open and the wind is blowing, the direction is frequently such as to cause a 5 pulsation of air, first in one direction and then in another direction through the window opening. When the wind does so pulsate, the flaps of the panel will alternately yield and close as just described.

10 My rods not only support the device as a whole but they prevent its flapping or blowing about.

My device may be quickly dried and then rolled up on the rods so as to occupy very 15 little space when not in use.

While I have, for the sake of clearness of illustration, shown a considerable opening between the side and bottom flaps yet it will be understood that this opening is negligible 20 and may be much reduced if desired.

What I claim is:

1. A device of the character described, comprising a flexible panel provided with means for engaging a window frame to hold the panel in position to act as a shield, said panel having loose flaps at its side edges to act, in conjunction with the sides of the window frame, as valves to prevent entrance of undesired air or rain. 25

2. A device of the character described, comprising a flexible panel provided with means for engaging a window frame to hold the panel in position to act as a shield, said panel having loose flaps at its side and bottom edges to act, in conjunction with the 30 sides and sill of the window frame, as valves to prevent entrance of undesired air or rain. 35

GRACE W. JENNINGS.
